C. S. ELLIXSON,
RAILWAY RAIL JOINT,
APPLICATION FILED MAR. 16, 1910.

Patented Apr. 6, 1915.

UNITED STATES PATENT OFFICE.

CORNELIUS S. ELLIXSON, OF GRANVILLE COUNTY, NORTH CAROLINA.

RAILWAY-RAIL JOINT.

1,134,321.

Specification of Letters Patent.

Patented Apr. 6, 1915.

Application filed March 16, 1910. Serial No. 549,678.

To all whom it may concern:

Be it known that I, CORNELIUS S. ELLIXSON, a citizen of the United States, residing in the county of Granville and State of North Carolina, have invented certain new and useful Improvements in Railway-Rail Joints, of which the following is a specification.

This invention relates to improvements in railway rail-joints and consists in a novel construction and combinations herein described and claimed.

The object of the invention is to construct the rail-joint of simple design and one upon which the concussion of moving cars will only suffice to tighten the fastenings of the joint.

The invention consists in the use of threadless bolts for holding the parts together and means for tightening said bolts by the movement of inclined planes longitudinally of the rails which inclined surfaces are arranged to engage corresponding beveled grooves in said bolts.

The invention further consists in the employment of a common means for moving said inclined planes and holding the same in the position required.

The invention also consists in having the bed-plate formed of a single piece, and a novel means for holding said bed-plate securely in position required. In the accompanying drawings forming a part of this application;—Figure 1 is a side elevation of the preferred form of my improved rail-joint. Fig. 2 is a longitudinal section on the line 2—2 Fig. 1. Fig. 3 is a transverse section on the line 3—3 of Fig. 2. Fig. 4 is a transverse section through the middle of the joint as on the line 4—4 of Fig. 2, and Fig. 5 is a side elevation of a modified embodiment of my invention.

Referring more particularly to the drawings 1 and 2 are a pair of rails having their adjacent ends abutting against each other. The abutting ends of said rails are arranged upon a bed-plate 3 while overlapping the ends of the rails and frictionally engaged in said bed-plate are a pair of fish-plates 4 and 5. The adjoining ends of the rails are cut away approximately at their center to receive a small block 6 arranged therein to prevent vertical movement of the rails in relation to each other, which generally causes a bumping action as the train runs

over the joint and which eventually causes a loosening of the joint.

The fish-plates 4 and 5 are arranged with rectilinear openings 7 and 8 directly opposite each other and arranged to be brought in alinement with corresponding openings 9 in the rails 1 and 2. A pair of plates 10 arranged on one side of the joint are provided with holes 11 adapted to receive the small ends 12 of flattened bolts 13. The body of the bolts 13 is arranged to pass through the openings 7, 8 and 9 in the fish-plates and rails securing the same together. The head 14 on the opposite end of the bolt is arranged to engage the fish-plate on the opposite side of the joint from that on which the plates 10 are secured. A plurality of grooves 15 are arranged in the plates 10, connecting the openings 11 in said plates. These grooves are cut in certain portions of the plate 10 which are beveled as shown at 12^a forming inclined planes. The bolts 13 are provided with cut-away portions 16 adjacent the head 12, forming shoulders 17, which are arranged to engage the inclined planes on the plates 10.

The ends of the plate 10 adjacent the center of the joint are provided with outwardly extending flanges 18 which flanges are provided with openings 19 to receive the end of a screw threaded bolt 20. A pair of nuts 21 are threaded on said bolt, each of which is adapted to engage the outer surface of one of the flanges 18.

The bed-plate 3 is arranged with upturned longitudinal flanges 22, the ends of which are bent as at 23. The lower flanges of the fish-plates 4 and 5 are formed toward their outer edges in the shape of a wedge 24. The upper edges of these fish-plates are beveled as shown at 25 and are arranged to fit tightly against the lower faces of the head of the rail.

In putting my joint together I first bring the ends of the rails adjacent each other and insert the block 6 in the notches formed in the ends of the rail. The fish-plates are then loosely mounted in position and the whole thrust in between the upturned flanges of the bed-plate. After bringing the openings in the rail web and fish-plates in alinement with each other the bolts 13 are thrust through these openings and also through the openings 11 in the plates 10 which plates are then pushed away from the center of the

joint in which operation the inclined planes 12^a engage the shoulders 17 on the heads of the bolts and exert a wedging action thereon tightening the joint and holding the parts 5 in position. These plates are secured in position by screwing the nuts 21 tightly against the flanges 18. This affords a very satisfactory and advantageous construction, as the only manner in which the joint can loosen 10 is by movement of the wedge plates, thus allowing a lateral movement between the rails and fish plates. However, the slightest movement of these wedge plates will bring their outwardly turned flanges more 15 firmly against the nuts on the bolt 20 and effectually lock them against rotation.

As shown in the drawings, the fish-plates are arranged at a slight angle to the vertical the upper edges extending outwardly from 20 the rail web. In tightening the bolts 13 the upper edges of the fish-plates are brought into engagement with the inclined lower faces of the heads of the rails. This gives extreme strength to the joint as the separate 25 pieces cannot be sprung apart and the only way in which the joint can become loosened is by breaking of one or more of the essential parts.

In the formation of the plates 10 the 30 flanges 18 might be formed of a separate piece of a slightly resilient nature, thus taking up in a further degree any play between the plates caused by any jarring of the joint and forming a perfect means for locking the 35 nuts 21 in position.

In Fig. 5 I have shown a slightly modified form of my invention in which two short bolts 26 and 27 are engaged by a turn buckle 28 any movement of which causes 40 either an approach or a separation of said bolts. These bolts are arranged with a boss 29 to engage the flanges 18 on the plates 10.

I have outlined herewith the preferred 45 form of my invention, but do not want to limit myself to the specific constructions and uses herein shown and described.

Copies of this patent may be obtained for five cents each, by addressing the "Commissioner of Patents, Washington, D. C."

Having thus described my invention what I claim as new and wish to protect by Letters Patent is:

1. In a rail joint, a pair of rails, fish plates 50 overlapping said rails, bolts connecting said fish plates and rails, oppositely disposed wedges arranged to engage said bolts, outstanding lugs on the adjacent ends of said wedges and a rigid adjustable connection 55 engaging said lugs for simultaneously moving said wedges in opposite directions and holding said bolts in position.

2. In a rail joint, pair of rails, fish plates 60 overlapping said rails, bolts connecting said fish plates and rails, reversely arranged wedges engaging said bolts and a common rigid means for simultaneously moving said wedges in opposite directions and holding 65 said bolts in position.

3. In a rail joint, a pair of rails, fish plates overlapping said rails, bolts connecting said fish plates and rails, oppositely disposed wedges arranged to engage said bolts, outstanding lugs on the adjacent ends of said 70 wedges, a threaded bar passing through openings on said outstanding lugs, and a pair of nuts threaded on said bar and adapted to engage said outstanding lugs for simultaneously moving said wedges in opposite 75 directions and holding said bolts in position.

4. In a rail joint, a pair of rails, fish plates overlapping said rails, bolts connecting said fish plates and rails, reversely arranged 80 wedges engaging said bolts and common means for simultaneously moving said wedges in opposite directions and holding said bolts in position and resilient means 85 for locking said tightening means in position.

In testimony whereof I affix my signature in presence of two witnesses.

CORNELIUS S. ELLIXSON.

Witnesses:

MAX HORN,
JAMES F. PURYEAR.
